DESIGN FOR A SPRAYER UNIT FOR PREVENTING OFFSET IN PRINTING OR THE LIKE

Glenn W. Tamm, Chicago, Ill., assignor to Binks Manufacturing Company, Chicago, Ill., a corporation of Delaware

Application December 4, 1939, Serial No. 88,670

Term of patent 7 years

To all whom it may concern:

Be it known that I, Glenn W. Tamm, a citizen of the United States and residing at Chicago, county of Cook and State of Illinois, have invented a new, original, and ornamental Design for a Sprayer Unit for Preventing Offset in Printing or the Like, of which the following is a specification, reference being made to the accompanying drawing, forming a part thereof.

Fig. 1 is a view in side elevation of a sprayer

unit for preventing offset in printing or the like showing my new design.

Fig. 2 is a top plan view of the same; and
Fig. 3 is an end view in elevation of the same.
I claim:

The ornamental design for a sprayer unit for preventing offset in printing or the like, substantially as shown.

GLENN W. TAMMEN.
